UNITED STATES PATENT OFFICE.

THOMAS RALPH ATKINS, OF LYNN, MASSACHUSETTS, ASSIGNOR OF ONE-HALF TO
RALPH M. DAVIS, OF LYNN, MASSACHUSETTS.

HOLDER FOR LICENSES, ETC.

Application filed June 17, 1924. Serial No. 720,553.

To all whom it may concern:

Be it known that I, THOMAS RALPH ATKINS, a citizen of the United States, residing at Lynn, in the county of Essex and 5 State of Massachusetts, have invented new and useful Improvements in Holders for Licenses, Etc., of which the following is a specification.

The invention relates chiefly to a holder 10 for the license carried by the driver of a motor vehicle, and its chief object is to enable such license to be securely confined on the body of the user in compact form, and readily accessible for exhibition to a traffic officer.

15 I attain this and other related objects by the improved holder construction hereinafter described and claimed.

Of the accompanying drawings forming a part of this specification—

20 Figure 1 is a side view of the folder constituting an element of the holder, the folder being unfolded for exhibition.

25 Figure 2 is a perspective view, showing the folder folded for insertion in the pouch constituting another element of the holder.

Figure 3 is a side view showing the preferred construction of the pouch in an opened condition.

30 Figure 3^a is a section on line 3^a—3^a of Figure 3.

Figure 4 is a section on line 4—4 of Figure 3.

Figure 4^a is a view similar to Figure 4 showing a modification.

35 Figure 5 is a perspective view, showing the pouch prepared for use.

Figure 6 is a section on line 6—6 of Figure 5.

Figure 7 is a view similar to Figure 6 showing another modification.

Figure 7^a is a perspective sectional view showing the modification shown by Figure 7.

Figure 8 is a perspective view showing the 45 entire holder.

The same reference characters indicate the same parts in all the figures.

My improved holder is composed of two parts, one of which is a two sided pouch 50 having on its inner side a support-engaging member whereby the pouch may be removably mounted on a support such as an apparel belt, and on its outer side a fastener member such as the stud member of a well known stud and socket or snap fastener, the

storage space of the pouch being between said members and having an open mouth. The other part of the holder is a flexible folder of sheet material such as thin flexible leather of greater area than the storage space 60 of the pouch and adapted to be folded to enter the pouch. The folder includes a flap adapted to overlap the outer side of the pouch and provided with a complementary fastener such as the socket member of the snap fastener above mentioned. The arrangement is such that the folder when folded and inserted in the pouch is retained therein by the inter-engagement of said fastener members, the flap constituting a handle whereby the holder may be inserted in and removed from the pouch when folded and held by the user when unfolded, so that an automobile license secured as hereinafter described to the folder and foldable therewith, may be conveniently held by the owner 70 in position to be exhibited to a traffic officer.

The preferred construction of the pouch is that shown by figures 3, 4, 5 and 6, the pouch including two duplicate body parts or sections 12 and 13 preferably of flexible leather and connected at opposite ends by rows 14 of stitches. The body part 12 constitutes the inner side of the pouch and is extended to form a flap portion 12^a projecting in one direction from the storage space between the body parts. The body part 13 constitutes the outer side of the pouch and is extended to form a flap portion 13^a projecting in the opposite direction 80 from the storage space. The flap portion 12^a is provided with socket fastener members 15, and the flap 13^a is provided with stud fastener members 16 to engage the members 15, so that when the flap portions are folded 85 across the body portion 12 as shown by Figure 6, they are coupled together and collectively constitute a support-engaging member adapted to bear on one side of a supporting strap 17 shown by dotted lines in 100 Figure 6. Said strap may be an apparel belt worn on the waist of the user, or it may be a portion of the suspenders of the user, or a strap otherwise supported. The flap 13^a constitutes the bottom of the storage space, 105 as shown by Figure 6. The described pouch construction is inexpensive and durable, involving the employment of only two pieces which are alike in form and size and are converted into a pouch by the operation of 110

- stitching the pieces together at 14, applying the fastener members and folding the flaps to form the support-engaging member, one of the flaps forming the bottom of the storage space. The body portion 13 is provided with an outwardly projecting stud fastener member 18 adapted to engage a complementary socket fastener member on the flap of the folder next described.
- 19 designates a folder which is preferably rectangular and composed of any suitably strong and flexible material, such as leather adapted to be folded on the intersecting lines 20 and 21 (Figure 1). When the folder 19 is folded, it assumes substantially the form shown by Figure 2, and is adapted to be inserted in the pouch, the folder when unfolded, having an area considerably greater than that of the storage space of the pouch.
- 20 The folder is provided at one of its edges with a flap 22, preferably integral with the folder and projecting therefrom at one side of the mid-length of said edge. This flap is provided with a socket fastener member 23 complementary to the member 18 on the pouch.
- 30 The arrangement is such that when the folder 19 is folded and inserted in the pouch, the flap 22 is adapted to overlap the outer side of the pouch and be detachably secured thereto by the inter-engagement of the fastener members 18 and 23.
- 35 The flap constitutes a handle adapted to be grasped by the thumb and finger of the user, so that the folder, when folded, may be conveniently inserted in and removed from the pouch, and held when removed and unfolded, in plain view of a traffic officer, so that a license sheet 25, confined on one 40 side of the folder, may be conveniently displayed.
- 45 A portion of the material of the folder is preferably cut out to form an orifice 26 at the intersection of the folding lines 20 and 21, so that when the sheet is folded its material is prevented from objectionably bulging at said intersection. Figure 1 shows a portion of the license sheet broken away to show the orifice 26.
- 50 The folder may be provided with any suitable means for confining the corner portions of the license sheet 25, preferably triangular pieces 27 of celluloid or other transparent material, each secured along two of its edges to the holding sheet by stitches 28, said pieces and the portions of the folder covered thereby constituting pockets in which the corner portions of the license sheet may be inserted. The license sheet 60 should be sufficiently flexible to enable it to be folded with the folder.
- 65 It is obvious that the folder may confine other articles of value, such as bank notes, railway tickets, etc.
- 65 It is obvious that the pouch may be simi-

larly engaged with a strap fixed to a handbag and located within the same, and with a strap secured to or worn on a garment for use by ladies.

A plurality of holders may be applied in 70 the manner described to a single holding member or strap.

Figure 4^a shows a modification which differs from the preferred construction above described, in that it includes a body part or 75 section 29 constituting the inner side of the pouch, and extended at its opposite ends to form the flap portions 12^a and 13^a, and a body part or section 30 secured by stitches 80 31 to the body part 29.

In the modification shown by Figures 7 and 7^a, the pouch is made by uniting two substantially rectangular pieces 32 and 33 of flexible leather along three edges by stitches 34, so that the pouch has an open 85 mouth. The piece 32 constituting the inner side of the pouch is provided with a support-engaging member 35, preferably a leather strip united at its end portions by stitches 37 and 38 to the pouch and having 90 an unattached central portion between which and the pouch an apparel belt 17 or other support may be inserted. The piece 33 constituting the outer side of the pouch is provided with the fastener member 18 adapted to engage the socket member 23 of the folder flap 22.

I claim:

1. An article of the character stated comprising a pouch having on one of its sides 100 means for engaging a support and provided on the outer face of its other side with a fastener member, and a flexible folder adapted to receive and display a sheet-like member and having at one edge a flap, which 105 projects from the folder when the latter is folded and constitutes a handle whereby the folder may be inserted in or removed from the pouch, the handle flap being provided with a complementary fastener member adapted 110 to engage the fastener member on the pouch when the folder is in the pouch.

2. An article of the character stated comprising a pouch having on one of its sides, between the planes of the mouth and bottom of the pouch, means for engaging a support and provided on the outer face of the other side with a fastener member, and a flexible folder adapted to receive and display a sheet-like member and having at one 120 edge a flap, which projects from the folder when the latter is folded and constitutes a handle whereby the folder may be inserted in or removed from the pouch, the handle flap being provided with a complementary 125 fastener member adapted to engage the fastener member on the pouch when the folder is in the pouch.

3. In a holder of the character stated, a pouch composed of two duplicate parts or 130

- sections of flexible sheet material, each including a body portion and a flap portion, stitches connecting opposite ends of the body portions, so that said portions form the sides 5 of a storage space, the flap portions projecting in opposite directions from said space, and complementary fastener members fixed to said flaps and adapted to be interengaged to couple the flaps together at the inner side 10 of the pouch, so that the flaps collectively constitute a support-engaging member adapted to bear on one side of a supporting strap interposed between the flaps and the inner side of the pouch, one of the flaps forming the bottom of the storage space, 15 the outer side of the pouch being provided with a fastener member adapted to engage a complementary fastener member on the flap of a folder inserted in said space.

In testimony whereof I have affixed my 20
signature.

THOMAS RALPH ATKINS.
